To all whom it may concern:

Be it known that I, ELEAZER KEMPSHALL, of Newton, in the county of Middlesex and State of Massachusetts, have invented and 5 produced a new and original Design for Lacing-Hooks, of which the following is a specification.

This invention relates to a new and original design for lacing-hooks; and it consists in the 10 novel features of shape and configuration hereinafter fully described and particularly claimed, and clearly illustrated in the drawings.

The essential feature of my design consists in an inverted dish-shaped head, said head being concavo-convex in cross-section and having an irregular edge, the head being connected by a neck with a securing member and 25 arranged with its concave side and irregular edge toward said securing member.

a represents the head of the lacing-hook, b its securing member, and f the neck that connects the head with said member. The 30 head a is concavo-convex in cross-section, and its edge is formed with irregularities f'. The securing member b is formed of one or more parts connected together and joined to the head by a neck f, the head being arranged 35 with its concave side and irregular edge toward said securing member.
